CLAIM

The ornamental design for bulk container, as shown and described.

DESCRIPTION

FIG. 1 is a perspective view of a bulk container showing our new design;

FIG. 2 is a front elevation thereof, the rear elevation being a mirror image thereof;

FIG. 3 is a left side elevational view thereof, the right side elevation being a mirror image thereof;

FIG. 4 is a top plan view thereof;

FIG. 5 is a bottom plan view thereof;

FIG. 6 is a front elevation thereof, in an empty and folded position; and

FIG. 7 is a side elevation of the FIG. 6 position thereof.

*Fig. 1.**Fig. 2.**Fig. 3.*

*Fig. 4.**Fig. 5.**Fig. 6.**Fig. 7.*
